CLAIM

The ornamental design for a vehicle park lamp, as shown and described.

DESCRIPTION

FIG. 1 is a left side elevational view of a left vehicle park lamp (the right vehicle park lamp being a mirror image and is not shown);

FIG. 2 is a right side elevational view thereof;

FIG. 3 is a front elevational view thereof;

FIG. 4 is a top plan view thereof;

FIG. 6 is a top perspective view thereof;

FIG. 7 is a bottom perspective view thereof;

FIG. 8 is a front elevational view of a left vehicle park lamp reflector (the right vehicle park lamp reflector being a mirror image and is not shown) for a headlamp without leveling; and, FIG. 9 is a front elevational view of a left vehicle park lamp reflector (the right vehicle park lamp reflector being a mirror image and is not shown) for headlamp with leveling.
